R. P. WRIGHT.

ADJUSTABLE AUTOMATIC PRESSURE ROLL RELEASE FOR CLOTHES WRINGERS.

APPLICATION FILED OCT. 2, 1916.

1,220,042.

Patented Mar. 20, 1917.

UNITED STATES PATENT OFFICE.

REA P. WRIGHT, OF WASHINGTON, DISTRICT OF COLUMBIA, ASSIGNOR TO JOHN FRANCIS HEMENWAY, OF NEW YORK, N. Y.

ADJUSTABLE AUTOMATIC PRESSURE-ROLL RELEASE FOR CLOTHES-WRINGERS.

1,220,042.

Specification of Letters Patent, Patented Mar. 20, 1917.

Application filed October 2, 1916. Serial No. 123,380.

To all whom it may concern:

Be it known that I, REA P. WRIGHT, a citizen of the United States, residing at Washington, in the District of Columbia, have invented certain new and useful Improvements in Adjustable Automatic Pressure-Roll Releases for Clothes-Wringers, of which the following is a specification, reference being had therein to the accompanying drawing.

This invention relates to certain new and useful improvements in adjustable automatic pressure roll release for clothes wringers, the object being to provide an automatic release which can be readily attached to a clothes wringer of the ordinary construction so that the pressure on the pressure rolls will be instantaneously released when the upper pressure roll moves a predetermined distance.

Another object of my invention is to provide an automatic release which is exceedingly simple and cheap in construction and one in which the releasing bars are slidably mounted on the wringer frame so as to cooperate with pivoted latches for holding the pressure means in predetermined position, said releasing bars carrying adjustable mounted members which are engaged by the shaft of the upper pressure roll when the same is moved vertically by a foreign object being drawn between the rolls.

Another and further object of the invention is to provide an automatic pressure release which can be adjusted on the pressure rolls when the upper pressure roll moves a certain distance upwardly, whereby the wringer to which the pressure release is attached can be used for wringing various thicknesses of clothes by adjusting the release.

Other and further objects and advantages of the invention will be hereinafter set forth and the novel features thereof defined by the appended claims.

In the drawings,

Figure 1 is a side view of the wringer partly in section showing the application of my improved construction of automatic pressure release thereto;

Fig. 2 is an end view;

Fig. 3 is a detail perspective view of the automatic release detached the parts being separated;

Fig. 4 is a detail sectional view of a

slightly modified form showing the bearing 30 on the upper pressure roll extended in position to engage the adjustable trip member 32 carried by the releasing bars.

Like numerals of reference refer to like parts in the several figures of the drawings.

In the drawings, 1 indicates a wringer frame composed of side bars 2 connected together at their lower ends by cross bars 3 and a rod 4, said side bars being provided with slotted upper portions in the upper end of which is movably mounted a top bar 5.

Slidably mounted within the lower portions of the slotted side bars 2 are superposed bearings 5 and 6 in which are mounted shafts 7 and 8 carrying pressure rolls 8 and 9 which are preferably provided with meshing gears, not shown, inclosed by gear casings 10. The upper bearings 6 carry spring supports 11 on which are mounted pressure springs 12 into which extend the depending lugs of bearing plates 13 carried by a pressure bar 14, said bearings 13 being engaged by pressure screws 15 mounted in threaded boxes carried by the top bar 5 so that the pressure means on the pressure rolls can be adjusted through the medium of these pressure screws.

Extending into the slot of the side bars transversely are screws 16 which extend into the apertured ears 17 of pivoted latches 18 which are adapted to engage the end of the top bar 5 as clearly shown in Fig. 1 so as to hold the top bar in position within the slotted side bars of the wringer frame. The latches 18 are provided with curved portions forming cam faces 19 which are adapted to be engaged by the cam-shaped upper ends 20 of releasing bars 21 which are slidably mounted in guide members 22 secured to the side bars, said releasing bars 21 carrying pins 23 working in slots 24 formed in the guide members 22 for holding the releasing bars in predetermined position in respect to the pivoted latches 18.

The lower ends of the releasing bars 21 are offset as shown at 25 and are provided with apertures 26 in which bolts 27 are arranged on which are slidably mounted trip members 28 with slots through which the bolts 27 extend, said bolts carrying thumb nuts 29 for clamping the trip members 28 in adjusted position upon the lower ends of the releasing bars 21 so that the lower edges thereof can be adjusted in respect to

the ends of the shaft 8 of the upper pressure roll 9 so as to allow the wringer to be used to wring various articles without setting into operation the releasing mechanism as by adjusting the trip members 28 the distance of travel of the upper pressure roll can be determined without tripping the mechanism.

In the modification shown in Fig. 4, the bearing 30 of the upper pressure roll is extended as shown at 31 under the adjustable trip member 32 carried by the releasing bar so that when the upper pressure roll is moved vertically by a foreign object passing between the rolls, the extended portion 31 will engage the trip member 32 so as to raise the releasing bar and move the pivoted latches out of the path of travel of the top bar to release said pressure means.

The operation of the automatic pressure roll release as herein shown and described is as follows:

Assuming that the wringer is being driven by power or hand through the medium of driving mechanism, not shown, carried by the lower shaft 7 of the pressure roll 8 when a foreign object is drawn between the pressure rolls the upper pressure roll 9 is moved vertically and the shaft 8 thereof is forced into engagement with the lower edge of the trip members 28 which causes the trip members to move vertically in order to bring the cam-shaped upper ends 20 into engagement with the cam faces 19 of the pivoted latches 18 which forces said latches outwardly from off of the ends of the movably mounted top bar 5 and allows the top bar 5 to move vertically which instantaneously releases the pressure on the pressure rolls.

From the foregoing description it will be seen that I have provided an automatic pressure roll release for clothes wringers which can be set so that the same will be tripped by the vertical movement of the upper pressure roll, whereby I am able to set the releasing mechanism into various positions in order to enable the clothes wringer to wring different articles without releasing the pressure roll means.

I claim:

1. A clothes wringer, comprising a frame having pressure rolls and pressure means for said rolls, retaining means for normally holding said pressure means in predetermined position, releasing members engaging said retaining means, adjustable trip members carried by said releasing members, said trip members being arranged in the path of travel of one of said pressure roll shafts and adapted to be engaged thereby on the upward movement of said roll.

2. A clothes wringer, comprising a frame having pressure rolls and pressure means for said rolls, means for normally holding said pressure means in predetermined posi-

tion, releasing members arranged to engage said retaining means, trip members adjustably carried by said releasing members, said trip members being actuated on the separation of said rolls for automatically releasing 70 said pressure means.

3. A clothes wringer, comprising a frame having pressure rolls and pressure means for said rolls mounted therein, movable members for holding said pressure means in 75 predetermined position, slidably mounted releasing members co-operating with said movable members, trip members carried by said releasing members, said trip members being arranged to be engaged by the shaft of one 80 of said pressure rolls on the upward movement thereof.

4. A clothes wringer, comprising a frame having pressure rolls and pressure means for said rolls, a top bar movably mounted 85 within said frame having means for adjusting said pressure means, movable members for holding said top bar in predetermined position within said frame, releasing members slidably carried by said frame, trip 90 members adjustably carried by said releasing members, and means actuated by the separation of said pressure rolls for moving said releasing members into engagement with said movable members for moving 95 said movable members out of the path of travel of said top bar.

5. A clothes wringer, comprising a frame having pressure rolls and pressure means for said rolls, a top bar movably mounted 100 within said frame having pressure screws for adjusting said pressure means, movable members mounted upon said frame for holding said stop bar in predetermined position therein, slidably mounted releasing members co-operating with said movable members, trip members adjustably mounted on the lower ends of said releasing members, said trip members being adapted to be engaged by the shaft of one of said pressure 110 rolls on the upward movement thereof for actuating said releasing members.

6. A clothes wringer, comprising a frame having pressure rolls and pressure means for said rolls mounted therein, pivoted 115 members for holding said pressure means in predetermined position, releasing members for moving said pivoted members in position to release said pressure means, trip members adjustably carried by said releasing members, said trip members being arranged to be engaged by the shaft of one 120 of said pressure rolls on the upward movement thereof.

7. A clothes wringer, comprising a frame having pressure rolls and pressure means for said rolls mounted therein, guide members secured to the sides of said frame, releasing bars slidably mounted in said guide members, trip members adjustably carried 125

5 by said releasing bars, said trip members being arranged in the path of travel of the upward movement of one of said pressure rolls, and movable members arranged in the path of travel of said releasing bars for holding said pressure means in predetermined position within said frame.

8. A clothes wringer, comprising a frame having pressure rolls and pressure means for said rolls mounted therein, a top bar movably mounted within said frame having means for adjusting said pressure means, pivoted latches mounted on the side bars of said frame for holding said top bar in predetermined position within said frame, said pivoted latches having cam portions, releasing bars slidably mounted on the side bars of said frame having cam upper ends adapted to coöperate with the 20 cam portions of said pivoted latches, said releasing bars being actuated by the upward movement of one of said pressure rolls so as to release said pressure means.

9. A clothes wringer, comprising a frame 25 having pressure rolls and pressure means for said rolls mounted therein, means for normally holding said pressure means in predetermined position, releasing members coöoperating with said means for moving 30 said means in position to release said pressure means, adjustable trip members carried by said releasing members, and means actuated by the separation of said pressure rolls engaging said trip members for releasing said pressure means.

10. A clothes wringer, comprising a frame having pressure rolls and pressure means for said rolls mounted therein, a top bar movably mounted within said frame having pressure screws for adjusting said pressure means, movable members for holding said top bar in predetermined position within said frame having cam portions, releasing bars slidably mounted on said frame having cam portions coöoperating with the cam portions of said movable members, trip members adjustably carried by the lower ends of said releasing bars, said trip members being arranged in the path of travel of the shaft of one of said pressure rolls, in the upward movement thereof for moving said releasing members upwardly to throw said movable members out of the path of travel of said top bar.

11. A clothes wringer, comprising a frame having pressure rolls and pressure means for said rolls mounted therein, pivoted latches mounted on the side bars of said frame for holding said pressure means in predetermined position, releasing members slidably mounted on the frame of said wringer, and adapted to engage said latches for moving said latches in position to release said pressure means, trip members carried by said releasing members, and means

actuated by the separation of said pressure rolls engaging said trip members for releasing said pressure means.

12. A clothes wringer, comprising a frame having pressure rolls and pressure means for said rolls, a top bar movably mounted within said frame having means for adjusting said pressure means, pivoted latches carried by the side bars of said frame for holding said top bar in predetermined position therein, releasing bars 70 slidably mounted on the side bars of said frame coöperating with said pivoted latches, and trip members adjustably mounted on the lower ends of said releasing bars and 75 arranged to be engaged by the shaft of one of said pressure rolls on the upward movement thereof for raising said releasing members to disengage said pivoted latches to release said pressure means.

13. A clothes wringer, comprising a frame having pressure rolls and pressure means for said rolls, a top bar movably mounted within said frame having pressure screws for adjusting said pressure means, pivoted latches carried by the side bars of said frame for holding said top bar in predetermined position within said frame, guide members secured to the side bars of said frame, releasing members slidably 95 mounted within said guide members, trip members adjustably mounted on the lower ends of said releasing members said trip members being engaged by the shaft of one of said pressure rolls on the upward movement thereof for moving said releasing members in position to release said pivoted latches for allowing said top bar to move vertically within said frame.

14. A clothes wringer, comprising a frame having pressure rolls and pressure means for said rolls, a top bar movably mounted within said frame having means for adjusting said pressure means, movable latches mounted upon the side bars of said frame for holding said top bar in predetermined position therein, guide members secured to the side bars of said frame, releasing members slidably mounted in said guide members, means for limiting the movement of said releasing members in said guide members, and trip members adjustably mounted on the lower end of said releasing members arranged to be engaged on the shaft of one of said pressure rolls on the upward movement thereof.

15. A clothes wringer, comprising a frame having pressure rolls and pressure means for said rolls, means for normally holding said pressure means in predetermined position, and means adjustably mounted on the frame of said wringer actuated by the vertical movement of one of said pressure rolls for releasing said means.

16. A clothes wringer, comprising a

frame having pressure rolls and pressure means for said rolls, releasing members adjustably mounted on the frame of said wringer adapted to be engaged by the shaft 5 of one of said pressure rolls on the upward movement thereof, movable members mounted on the frame of said wringer for holding said pressure means in predetermined position, said movable members being engaged 10 by said releasing members to release said pressure means.

17. A clothes wringer, comprising a frame having pressure rolls and pressure means for said rolls mounted therein, movable members for holding said pressure means in predetermined position, slidably mounted releasing bars coöperating with said movable members, trip members adjustably mounted upon said slidably mounted members, and means actuated by the vertical movement of one of said pressure rolls engaging said trip members for moving said releasing bars in position for actuating said movable members for releasing 25 said pressure means.

18. A clothes wringer, comprising a frame

having pressure rolls and pressure means for said rolls mounted therein, movable members for holding said pressure means in predetermined position, movable mounted 30 releasing bars coöperating with said movable members, trip members carried by said releasing members, said trip members being actuated by the vertical movement of one of said pressure rolls for releasing said 35 pressure means.

19. A clothes wringer, comprising a frame having pressure rolls and pressure means for said rolls mounted therein, pivoted members for holding said pressure means in predetermined position, movable members coöperating with said pivoted members for releasing said pressure means, trip members carried by said movable members, and means actuated by the vertical 40 movement of one of said pressure rolls engaging said trip members for actuating said 45 releasing members.

In testimony whereof I hereunto affix my signature.

REA P. WRIGHT.
